UNITED STATES PATENT OFFICE.

PERCY EDWARD CORRELL, OF ADELAIDE, SOUTH AUSTRALIA, AUSTRALIA.

REFLECTOR.

1,413,315.

Specification of Letters Patent. Patented Apr. 18, 1922.

Application filed September 5, 1919. Serial No. 321,921.

To all whom it may concern:

Be it known that I, PERCY EDWARD CORRELL, a subject of the King of Great Britain and Ireland, residing at Verco Buildings, 5 North Terrace, Adelaide, State of South Australia, Commonwealth of Australia, have invented certain new and useful Improvements in Reflectors, of which the following is a specification.

10 This invention relates to certain new and useful improvements in reflectors applicable to headlamps for vehicles and to other lamps.

15 A primary object of the invention is to provide an improved reflector for headlamps for vehicles and the like whereby a roadway in front of a vehicle equipped therewith may be efficiently illuminated at night from a point in the proximity of the vehicle to a point well in advance thereof; the illumination thereby afforded being entirely free from "streakiness" such as is commonly present by many headlamps at present in use, and which "streakiness" results from the formation on the roadway of distorted or 20 imperfect or other images so as to constitute a source of discomfort or danger to drivers of vehicles, and pedestrians by reason of the eyes of such being temporarily "blinded" by light of excessive intensity.

25 With a view to the attainment of the hereinbefore stated object, the invention comprises a reflector having a highly light-diffusive, light-reflecting surface and a very slightly light-diffusive light reflecting surface.

30 The elimination of "streakiness" in road-illumination is considered and has been found to be a matter of very great importance. The illumination of a roadway is also very 35 much clearer and more uniform by the elimination of "streakiness".

Reference is made to the accompanying drawings in which like characters of reference indicate like parts in both views. Figures 1 and 2 represent respectively sectional and front views of the improvement. Referring to the drawing B is a paraboloidal reflector formed by spinning or otherwise in accordance with well known practice from 45 sheet-metal, and having its concave light reflecting surface electro-silver plated so as to ensure high light reflectivity thereof, serving to concentrate and to direct or re-direct rays of light from the helical filament A

impinging thereupon—the said filament being suitably positioned just inside or behind the focus of the paraboloidal reflector so that practically the whole of the light reflected from the lower portion or half of the reflector is downwardly directed. In my reflector prior to applying the coating of silver the inner surface of the reflector is frosted, granulated or roughened. The upper portion *a* of the reflector is heavily frosted, granulated or roughened so that when the silver coating is applied the frosted granulated or roughened surface is substantially retained, thereby "enlivening" or rendering the surface highly reflecting. The lower portion *b* of the reflector is slightly frosted, granulated or roughened, so that the frosted, granulated or roughened surface presents a practically smooth surface when the coating of silver is applied. It is to be understood that the light-diffusivities of the said upper and lower portions or halves of the said concave surface of the said reflector may be varied within such limits as may be compatible with the respective required functionings thereof, it being understood that with respect to the slight "light-diffusivity" the slightest such "light-diffusivity" which will ensure the desired elimination of "streakiness" from the illumination afforded is preferably employed.

The slightly light-diffusive surface prepared as aforesaid will be seen to exhibit a slight "sheen"—such being an appearance quite distinct from that of a true frosting as generally denoted by such term.

What I claim is:—

1. A reflector having its concave surface roughened, one half of the surface being rougher than the other half and the whole surface coated with silver.

2. A reflector having a concave granulated surface, the upper half being heavily granulated and the lower half slightly granulated, and a coating of silver on the said granulated surface.

In testimony that I claim the foregoing as my invention I have signed my name in the presence of two subscribing witnesses this 7th day of July 1919.

PERCY EDWARD CORRELL.

Witnesses:

CHARLES NICHOLAS COLLISON,
ARTHUR GORE COLLISON.
